UNITED STATES PATENT OFFICE.

HUGO R. SWANSON AND WILLIAM H. ROBINSON, OF BROOKLYN, NEW YORK, AS
SIGNORS TO TRIANGLE KAPOK MACHINE CORPORATION, OF NEW YORK, N. Y., A
CORPORATION OF DELAWARE.

APPARATUS FOR PREPARING FELT FILLERS FOR MATTRESSES.

Application filed August 28, 1926. Serial No. 132,142.

This invention relates to a machine for preparing fillers for mattresses made of felt material.

One of the objects of this invention is the provision of a novel combination of elements to form a machine adapted to construct mattress fillers from cotton linters, and the like.

A still further object of this invention is the provision of a machine of this nature which is adapted to construct the filler of a plurality of layers superimposed one on the other and compressed into a compact mass.

A still further object of this invention is the provision of a series of carding drums adapted to arrange the stock from which the filler is made in parallel lines, and to prevent the adherence thereto of any of the stock.

A further object of this invention is the construction of a machine of this nature which is relatively simple mechanically, and which is so constructed as to be efficient in operation.

These and many other objects which are sought by this invention are secured thereby and will appear in the following description.

This invention resides substantially in the combination, construction, arrangement, and relative location of parts, as will be more fully disclosed in the following specification.

Referring to the drawings, in which the same reference numerals will be used in the several views to indicate the same or similar parts,

Fig. 1 represents a side elevational view of our machine with some parts broken away.

Fig. 2 represents a vertical cross-sectional view of one of the carding drums used in our invention.

Fig. 3 is a vertical diametral cross-sectional view of one of these drums.

Fig. 4 is an enlarged detailed view taken on the line 4—4 of Fig. 2.

Fig. 5 is an enlarged view showing the method of attaching the carding projections to the carding drum.

Fig. 6 is a side elevational view of our completed device taken on the side opposite to that of the view of Fig. 1.

Fig. 7 is a top plan view of our device.

As far as we are aware, no successful ma-

chine has been provided by means of which cotton linters and other felt stock materials can be properly prepared for use in making fillers for felt mattresses. We have therefore devised a machine which is particularly adapted for this purpose as will appear more fully hereinafter.

Referring to the drawings, a closed chamber is shown at 1, provided with side walls comprising the parts 2 and 3. The side wall 60 is divided into these two parts along a line passing through the centers of the gear wheels shown in Figs. 1 and 6. At each point where the drums extend through the walls, as shown in Fig. 2, the casing is 65 notched out along this separating line to provide openings through which the drums project. The chamber 1 is supported on a framework 4, which, in turn, is mounted on the roller 5 for convenience in moving the 70 device from place to place. Mounted in bearing 6 on the framework 4, are the drums 7, over which pass the endless belt, chain, or other suitable conveyor 8. The chamber is closed by means of the removable top piece 75 or plate 8', to permit of access to the interior, if desired. A large flat plate 9, which just fits within the case 1, is provided with the integral projecting arm 10, forming a gear rack which meshes with the small gear 80 wheel 11 supported in the brackets 12, on the top of the housing, and adapted to be rotated by means of the handle 13. This plate 9 is vertically movable within the chamber 85 1, for a purpose which will be described shortly.

An electric motor or other suitable power device 14, is supported on the top of the casing and connected by means of a belt or chain 15 to the transversely extending shaft 16, mounted in the bearing 17 on top of the casing. Two gear wheels are provided, one on each end of the shaft 16, over which pass the chains 18 and 19. The chain 19 on the front side of the chamber passes over a gear 95 wheel 20 mounted on a short stud secured to the side housing. Mounted for rotation with the gear wheel 20, is a gear 20', which in turn meshes with the large gear 22, attached to the end wall 23 of the carding drum 25. 100

A somewhat similar end wall 24 is provided for the other end of the drum. The drum is provided with a large number of perforations 27, and a large number of projecting fingers 26, which are suitably secured to the surface of the drum as shown, for instance, in Fig. 5.

Mounted within the cylinder is a substantially circular deflecting plate 29, supported at each end by the cap pieces 28, which have projections 30 extending through holes in the end plates 23 and 24 of the carding drum. It will be noted, for instance, in Fig. 3, that the deflecting plate 29 comprises a substantial cylinder with a portion of its surface interrupted to form an opening throughout its length. The projection 30, at the left hand side of Fig. 2, and as shown in Fig. 4, is reduced at its end to provide a square portion 31 which extends into the supporting bar 32, which, in turn, extends throughout the length of the machine as shown in Fig. 1. There are a plurality of these drums, all driven by means of the large connecting gears 22, and the smaller idle gears 22', as shown in Fig. 1.

Extending through the projections 30, is a horizontal shaft 33, on which is mounted a fan 34 of any suitable shape. The shaft 33 is supported in the side bar 32, and a similar side bar 37 on the other side of the machine, and has secured thereto, the small gear 35, which meshes with a large gear 36, as shown in Figs. 2 and 6. Mounted on a short stud 38 is a gear 21, meshing with the gear 36, and caused to be rotated by a gear over which the chain 18 passes. It will be noted that the extension 30 on the right hand plate 28 as viewed in Fig. 2 is not provided with a square portion, as is the left hand extension 30. If so desired, and as is shown in Fig. 3, the right hand cap 24 for the carding drums may be provided with a series of openings, or may be made in the form of spokes 25', to permit the admission of air when the fan 34 is operated.

Mounted above the conveyor 8, and adjacent to one end is a suitable roller 40 which may be driven by means of the conveyor moving apparatus, or merely by reason of its contact with the felt material, and is so arranged that the material is compressed as it passes out through the exit in the chamber 1. Extending transversely across the chamber, is a plurality of T-bars 38, which support the grooved open pans 39, one adjacent to each of the carding drums as shown in Fig. 1. Near the top of the casing is provided an opening 41, through which the material may be delivered to the chamber 1, either by a current of air, by hand, or other suitable means.

It will be seen then that the carding drums are rotated by means of the belt 19, through the agency of the gears 20, 20', 22, and 22',

while the revolving fans are operated through the agency of the belt or chain 18, gear 30', gear 21, gears 36, and gears 35. We have not shown any apparatus for driving the conveyor and the drum 40, since it will be readily apparent to anyone skilled in the art, how these may be operated,—for instance, they can be driven independent of the drum and fan operating mechanism, or they may be driven directly therefrom. Stops may be placed on the inside of this casing or on rack 10 to prevent the plate 9 from coming in contact with the picker drums.

The operation of the device is somewhat as follows: The plate 9 is moved to the top of the chamber by means of the gear rack structure on top of the casing, and material is fed to the chamber through the opening 41, in any suitable manner until the chamber is completely full. The plate 9 is then released and allowed to press downward on the mass of stock within the casing. The electric motor, or other power means is started up, and the carding drums will gradually draw the material down onto the pans 39, and arrange the fibres in more or less parallel relationship with respect to each other. When the material F has moved along the pan until it comes opposite the opening in the deflecting plate 29, the fans blow any of the stock from the drum which might be adhering thereto. A series of layers of felt material F, (see Fig. 1) is provided, one upon the other, and as the conveyor moves along, the material is fed out of the machine at the exit point adjacent the drum 40, and is compressed to any suitable degree by means of this drum, which may, in actual construction, be mounted so as to be vertically adjustable with respect to the conveyor. Where it is desired, a suitable mouth may be attached to the machine at the point of exit over which the mattress covering may be slipped, so that the lining may be fed directly into the casing. When desirable, this mouthpiece may be made adjustable in size to fit the particular mattress to be filled.

It will be apparent to those skilled in the art, therefore, that we have prepared a novel device for constructing felt fillers for mattresses, embodying novel principles of construction.

As the stock is consumed from the chamber 1, the plate 9 descends under the action of gravity, and maintains a uniform pressure on the material as it is fed to the drums. When the chamber is empty, or substantially so, the device is stopped, and plate 9 is raised, so that the casing may again be filled.

We are aware that many changes in the details of construction, and relative arrangement of parts will suggest themselves to those skilled in the art, and we do not, there-

fore, desire to be limited to the particular physical construction shown, but rather to the scope of our invention as we define it in the appended claims.

5. What we seek to secure by United States Letters Patent, is:—

1. In a machine of the kind described, the combination with a closed chamber and a plurality of revolving drums having projections thereon, of a conveyor disposed at the bottom of said chamber and gravity means for feeding the stock to said drums under uniform pressure, said drums and conveyor operating to feed the stock from the bottom 15 of the chamber in a compact layer.

2. In a machine of the kind described, the combination with a closed chamber, a plurality of picker drums in said chamber, and a pan disposed adjacent each drum of a conveyor in the bottom of said chamber.

20 3. In a machine of the kind described, the combination with a closed chamber, a plurality of picker drums in said chamber, and a pan disposed adjacent each drum of a conveyor, of an endless belt conveyor in the bottom of said chamber.

30 4. In a machine of the kind described, the combination with a closed chamber, a plurality of picker drums in said chamber, and a pan disposed adjacent each drum of a conveyor in the bottom of said chamber, and means adjacent one end of the conveyor for compressing the material between it and the conveyor as it leaves the machine.

35 5. In a machine of the kind described, the combination with a closed chamber, a plurality of picker drums in said chamber, and a pan disposed adjacent each drum of a conveyor, of an endless belt conveyor in the bottom of said chamber, and means for compressing the material on the conveyor as it leaves the machine.

40 6. In a machine of the type described, the combination with a chamber adapted to receive the stock, a plurality of picker drums in said chamber, a pan adjacent each drum, means for feeding the stock to the drums under uniform pressure, and means for operating said drum of a conveyor disposed in said chamber for feeding the finished product from the machine.

45 7. In a machine of the type described, the combination with a chamber adapted to receive the stock, a plurality of picker drums in said chamber, a pan adjacent each drum, means for feeding the stock to the drums under uniform pressure, means for operating said drum of a conveyor disposed in said chamber for feeding the finished product from the machine, and means for compressing the finished product on the conveyor as it leaves the machine.

50 8. In a machine of the type described, the combination with a chamber for receiving the stock, a plurality of perforated picker

drums in said chamber, means for forcing air through the perforations in said drums, and a pan adjacent each drum of means in the bottom of said chamber for delivering the finished product from said chamber. 70

9. In a machine of the type described, the combination with a chamber for receiving the stock, a plurality of perforated picker drums in said chamber, means for forcing air through the perforations in said drums, 75 and a pan adjacent each drum of means in the bottom of said chamber for delivering the finished product from said chamber, and means for compressing the finished product on said delivering means at the point of delivery.

10. In a machine of the type described, the combination with a chamber for receiving the stock, a plurality of perforated picker drums rotatably mounted in said chamber, a pan adjacent each drum, means in each drum for creating an air pressure therein, means in each drum for confining the escape of air to a limited area in the direction of the pans and means for operating 90 said drum and pressure creating means of means in said chamber for feeding the finished product therefrom.

11. In a machine of the type described, the combination with a chamber for receiving the stock, a plurality of perforated picker drums rotatably mounted in said chamber, means for supplying the stock to the drums under constant pressure, a pan adjacent each drum, means in each drum for creating an air pressure therein, means in each drum for confining the escape of air to a limited area in the direction of the pans, and means for operating said drums and pressure creating means, of means in said 100 chamber for feeding the finished product therefrom. 105

12. In a machine of the type described, the combination with a chamber for receiving the stock, a plurality of perforated picker drums in said chamber, a pan adjacent each drum, said drum being adapted to blow the stock onto said pans, and means for feeding the stock to said drums.

13. In a machine of the type described, the combination with a chamber for receiving the stock, a plurality of perforated picker drums in said chamber, a pan adjacent each drum, said drum being adapted to blow the stock onto said pans, and means for feeding the stock to said drums, of a conveyor in the chamber for removing the finished product. 115 120

14. In a machine for making a mattress filling from stock comprising a plurality of layers, the combination with a chamber having means therein for uniformly feeding the stock, a plurality of picker drums in said chamber, and a pan adjacent each drum whereby a layer of the filling is made by 125 130

each drum, of means for compressing the layers and feeding them from the chamber as a unit.

15. In a machine of the type described, the combination with a chamber, a plurality of perforated picker drums in said chamber, a pan adjacent each drum, means in each drum for forcing stock from the surface of each drum onto its pan of means for feeding the stock to the drums.

16. In a machine of the type described, the combination with a chamber, a plurality of perforated picker drums in said chamber, a pan adjacent each drum, means in each drum for forcing stock from the surface of each drum onto its pan of means for feeding the stock to the drums and means for feeding the finished product from the machine.

17. In a machine of the type described, the combination of chamber having pressure feeding means therein, a plurality of parallel perforated picker drums therein, a revolving fan in each drum, a shield in each

drum for directing the air through the perforations in a limited area, a pan adjacent 25 each drum, and means for operating said drums and fans, of means for conveying the finished product from the machine.

18. In a machine of the type described, the combination of chamber having pressure 30 feeding means therein, a plurality of parallel perforated picker drums therein, a revolving fan in each drum, a shield in each drum for directing the air through the perforations in a limited area, a pan adjacent 35 each drum, and means for operating said drums and fans, of means for conveying the finished product from the machine, and means for compressing the finished product at the point of delivery.

In testimony whereof we have hereunto set our hands on this 11th and 18th days of August A. D., 1926.

HUGO R. SWANSON.
WILLIAM H. ROBINSON.
